UNITED STATES PATENT OFFICE.

JOHN FLINN ANCONA, OF ROCHESTER, NEW YORK.

PRINTING AND CUTTING MACHINE.

1,222,914.

Specification of Letters Patent. Patented Apr. 17, 1917.

Application filed July 21, 1913. Serial No. 780,244.

To all whom it may concern:

Be it known that I, JOHN FLINN ANCONA, a citizen of the United States, residing at Rochester, in the county of Monroe and State of New York, have invented or discovered certain new and useful Improvements in Printing and Cutting Machines, of which is a specification, reference being had therein to the accompanying drawings.

10 This invention has for its general and primary object to provide mechanism for conveniently and economically producing relatively long and narrow strips or tapes of paper or the like having continuous reading or similar matter printed on one or both sides thereof.

In another application for Letters Patent filed by myself and John Feger Ancona, May 13, 1913, Serial No. 767,326, there is 20 described a novel reading device wherein is employed an elongated reading strip having reading matter arranged in a single, continuous column on each side thereof, the reading matter being oppositely disposed on 25 the opposite sides of the strip. Said reading strip is used in connection with a reading frame employing a pair of rolls, the strips being gradually reeled from one roll to the other during the reading of one side 30 thereof, whereupon the frame is reversed and the strip gradually rereeled upon the first roll and the opposite side read.

A more particular object of the present 35 invention is to provide printing and cutting mechanism for producing reading strips capable of use in a reading device of the above character, said printing mechanism being of the approved rotary type and the strips being produced in continuous form, that is to 40 say being free from joints such as would be occasioned by printing the strips in sections and joining them together. It will be understood in this connection that a reading strip, in order to be conveniently handled, should 45 be only a few inches wide, and that in order to include upon a single strip of this width a complete novel or similar work in type of a size suitable for easy reading a strip many feet in length would be required.

50 To this end the invention contemplates the provision of rotary printing mechanism capable of printing a continuous or unbroken column or line of greater length than the length or circumference of the printing cylinder, and also the provision of improved 55 cutting mechanism especially adapted to

sever into strips a web printed by the printing mechanism above referred to, said printing and cutting mechanisms furthermore each involving certain novel features of 60 more general utility as will hereinafter more fully appear.

The foregoing and other objects of the invention, together with means whereby the same may be carried into effect, will best be 65 understood from the following description of one form or embodiment thereof illustrated in the accompanying drawings. It will be understood, however, that the construction described and shown has been 70 chosen for illustrative purposes merely and that the invention may be embodied in other forms without departing from the spirit and scope thereof. It will be furthermore understood that the utility of the invention is 75 not limited to the particular purpose above outlined, but that certain or all features thereof, either separately or in combination with one another according to the requirements, might be used to equal advantage for 80 other purposes and in other relations.

In said drawings:

Figure 1 is a side elevation of a combined printing and cutting or slitting machine constructed in accordance with the invention.

Fig. 2 is a longitudinal sectional view illustrating diagrammatically the relationship and the coöperation of the printing, impression, and slitting cylinders.

Fig. 3 is an elevation, partly broken away, 90 of the first printing cylinder and its coöperating impression cylinder as viewed from the line 3—3, Fig. 1, looking in the direction of the arrow adjacent said line.

Fig. 4 is a similar but fragmentary view 95 of the second printing and impression cylinders similarly viewed from the line 4—4, Fig. 1.

Figs. 5 and 6 are enlarged detail sectional views illustrating the means for securing the 100 printing plates upon the printing cylinders.

Fig. 7 is a detail view of one of the end clamping devices removed.

Fig. 8 is a similar view illustrating a modified construction.

Fig. 9 is an elevation partly broken away 105 of the cutting or slitting cylinders as viewed from the line 9—9, Fig. 1, looking in the direction of the arrow.

Fig. 10 is a section on the line 10—10, 110 Fig. 9.

Fig. 11 is an enlarged detail sectional view

of portions of the coöperating helical slitting knives and portions of the cylinders to which they are secured.

Fig. 12 is a plan view of the paper web, illustrating the disposition of the printed matter thereon and the manner in which the reading strips are produced therefrom.

Figs. 13 and 14 are enlarged plan views illustrating the opposite sides of a single reading strip, the portions of the web from which said strip is severed being shown in dotted lines.

In Fig. 1, 20 denotes the machine frame, 21 and 22 the upper and lower printing cylinders carried by shafts journaled in said frame, 23 and 24 the lower and upper impression cylinders, also carried by shafts journaled in said frame and coöperating respectively with the printing cylinders 21 and 22, 25 a bed or table supported by the frame and over which the web 26 passes, 27 guide rolls, 28 feed rolls for the paper web, and 29 inking rolls for the printing cylinders. Except as hereinafter described the parts thus far enumerated may be of any suitable or well known construction common to the usual rotary or cylinder printing press. As shown, power is communicated to the machine from any suitable source through a belt 30 coöperating with a pulley 31 on the shaft of the cylinder 21, on which shaft is secured a gear 32 meshing with the gear 33 on the shaft of the impression cylinder 23, and with a gear 34 which in turn meshes with the gear 35 on the shaft of the impression cylinder 24, said gear 35 also meshing with a gear 36 on the shaft of the printing cylinder 22. By these connections the cylinders 21, 22, 23 and 24 are all driven in unison by the belt 30. In order to provide for the proper registry of the printed matter on the opposite sides of the web one pair of cylinders, herein the cylinders 22 and 24 are adjustably mounted, the shafts of said cylinders being journaled in slides 37 mounted in guides 38 on the frame, said slides being adjusted to any desired position in said guides and held in such position by means of adjusting screws 39. To compensate for the adjustment of the cylinders 22 and 24, the shaft of the gear 34 is similarly journaled in slides 40 mounted in guides 41 on the machine frame and movable therein by means of adjusting screws 42.

In accordance with the process for which the present machine is particularly adapted the elongated, continuous strips of reading matter are printed upon the web 26 in diagonal positions, the said strips (designated by the numeral 43 in Fig. 12) commencing at points adjacent one edge of said web and terminating at points adjacent the opposite edge thereof. When so printed it will be seen that by slitting the web diagonally a continuous strip of the proper dimensions

and containing the desired reading matter in suitable arrangement may be produced. For the particular purpose referred to at the beginning of this specification each strip is printed on both sides, the lines of reading matter running cross-wise of the strip and said reading matter being oppositely disposed on the opposite sides of the strip. In other words the successive lines of said reading matter may be considered as running downwardly or toward the right on one side of the strip, as shown in Fig. 13, and upwardly or toward the left on the reverse side, as shown in Fig. 14, so that the matter at the upper or right end of the side of the strip shown in Fig. 14 forms a continuation of the matter at the lower or right end of the side of the strip shown in Fig. 13.

In order to print the continuous diagonal strips of reading matter shown in Fig. 12 upon the web 26, the printing surfaces or impression elements of the cylinders 21 and 22 are helically arranged thereon and preferably extend continuously from end to end thereof. In other words each printing surface may be considered as consisting of relatively short lines of type arranged in a long continuous column, the several lines being each perpendicular to the length of the column, and the column itself being continuously and helically wound or wrapped about the cylinder. A suitable construction is illustrated in Figs. 3 and 4. Inasmuch as the construction of the two printing cylinders is substantially identical, with the exception that the pitch of the helices thereon is in opposite directions, only the upper cylinder, shown in Fig. 3, will be described in detail, the corresponding parts on the lower cylinder shown in Fig. 4 being designated by the same numerals with the exponent "x" added. It will of course be understood that the character of each printing surface will be such as to produce the desired arrangement of the reading matter on the opposite sides of the strip as will, it is thought, be obvious by a comparison of Figs. 3 and 4.

The electrotype or stereotype plate 44 (hereinafter generically referred to as the printing plate) comprises a suitable number of sections, herein shown as four, secured to the outer surface of the printing cylinder 21 by means hereinafter more fully described. Each plate section is formed with portions 45 of the helical printing surface between which are arranged grooves 46, the portions of the printing surface on the several plate sections and the arrangement of the sections being such that when said sections are assembled on the cylinder the helical printing surface portions will combine and join to form a complete helix extending from one end of the cylinder to the other, as above stated. The lines of division 47 between the several printing plate sections are arranged

to cross each portion or convolution of the printing surface 45 in a direction perpendicular to the helix so as to avoid cutting the lines of type. To this end the plate sections 5 are preferably formed with interengaging serrated edges, the portions 470 of said edges which cross the coils or convolutions of the printing surface being perpendicular to said helix, and the portions 471 between said convolutions being substantially parallel to said helix.

For securing the plate sections to the printing cylinder there are provided end clamping blocks 48 (see also Fig. 6) formed 15 with grooves 49 to receive the ends of the cylinder 21 and with beveled edges 50 to cooperate with the correspondingly beveled edges of the printing plates 44 to clamp said plates to the surface of the cylinder, said clamping blocks being secured to the cylinder 20 by means of bolts 51 passing through said blocks and entering tapped openings in the ends of the cylinder. Preferably the clamping blocks 48 are made of the annular 25 form shown in Figs. 2 and 7, each block comprising a number of sections equal to the number of printing plate sections. Alternatively, if desired, said blocks may be of the short form shown in Figs. 3, 4 and 8, a suitable number of these blocks being arranged about each end of the cylinder, preferably 30 adjacent the joints between the printing plate sections. For securing the printing plates to the cylinder at points intermediate their ends said cylinder (see Figs. 3, 5 and 6) is formed on its outer surface with an undercut or dove-tailed helical groove 52 corresponding in form and arrangement to the helical groove 46 between the coils or 35 convolutions of the helical printing surface 45 on the complete printing plate. Located within the groove 52 are dove-tailed blocks 53 having tapped openings to receive screws or bolts passing through the bottoms of the 40 grooves 46 in the printing plate sections.

The web 26 in its successive passage by the printing cylinders 21 and 22 is printed on both sides in inclined strips 43, as shown in Fig. 12 and as heretofore more fully described. It will be understood that at each 50 complete rotation of a printing cylinder one end (that shown at the right in Fig. 3) of the printing surface 45 is brought into engagement with the web at one edge thereof and the opposite end of said printing 55 surface passes out of engagement with said web at the opposite edge thereof, so that at each rotation of the cylinder the printing of one strip is completed and the printing of another strip begun while a number of intermediate strips, equal to the number of convolutions of the helix on the cylinder, will be in various stages of completion. After the first end of the printing surface is 60 brought into engagement with the web it re-

mains continuously in engagement therewith during a number of rotations of the cylinder equal to the number of convolutions of the helix, causing a continuous diagonal strip or column to be printed as above described. Each strip will be printed on both sides by the upper and lower printing cylinders respectively, the helical printing surfaces on said cylinders being so arranged with respect to one another as to cause the 75 printing on the opposite side of each strip to register properly, any adjustment necessary to accomplish this result being effected by means of the slides 37 and screws 39.

After passing the printing cylinders the web 26 is cut or slitted to separate the printed strips 43 from one another. To this end the following cutting or slitting mechanism is provided reference being had particularly 80 to Figs. 1, 9, 10 and 11.

55 and 56 denote upper and lower slitting cylinders carried by shafts 57 and 58 journaled in slides 59 mounted in guides 60 on the frame 20 and movable in said guides by 90 means of adjusting screws 61. The lower cylinder 56 is keyed to the shaft 58 upon which is secured a sprocket wheel 62 connected by a chain 63 to a sprocket 64 on the shaft of the lower printing cylinder 22, said 95 chain 63 passing over an adjustable idler sprocket 65 carried by the frame. Secured to the cylinder 56, as by bolts 68, is a gear 66 which meshes with a gear 67 keyed to the shaft 57. By these connections the shafts 100 57 and 58 are rotated in unison from the shaft of the lower printing cylinder 22.

On the surfaces of the cylinders 55 and 56 are helical slitting knives 69 and 69* respectively. The form and arrangement of 105 these knives upon the cylinders correspond to the form and arrangement of the grooves 46 and 46* in the printing plates upon the printing cylinders. The slitting knives 69 and 69* are preferably formed in sections of 110 suitable length secured to the cylinders by bolts or screws 70 (see Fig. 11) and ground when in place in order to produce perfect helices. In order to provide a perfect cutting edge the meeting sides on the knives 115 69 and 69* are preferably slightly undercut, as shown in Fig. 11. In order to insure a close engagement between the coöperating slitting knives, thereby providing for a positive and efficient shearing action, the 120 following construction is provided.

The upper slitting cylinder is not keyed to the shaft 57 but is loosely mounted thereon and is provided with an inwardly turned flange 71 formed with a series of openings to 125 receive pins 72 projecting inwardly from a ring 73 rotatably mounted within a cylindrical flange 74 on the gear 67 and held in place by means of a rib or retaining ring 75 suitably secured to the inner face of said 130

flange 74. The ring 73 is formed with inwardly projecting lugs 76 between which and the lugs 77 on certain of the spokes of the gear 67 are interposed springs 78 whose tension is adjustable by means of screws 79 passing through the lugs 77. The rotation of the gear 67 is yieldingly transmitted through the springs 78, ring 73 and pins 72 to the cylinder 55. The arrangement of the parts is such that the tension of the springs 78 tends at all times to produce a rotation of the cylinder 55 with respect to the cylinder 56 in a suitable direction to hold the co-operating edges of the helical knives 69 and 69^x in close engagement with one another. Moreover the connection between the cylinder 55 and rings 73 through the pins 72 is such as to permit said cylinder, by moving the same a slight distance longitudinally on the shaft 57, to be adjusted to different angular positions on said shaft (the pins 72 being engaged with different openings in the flange 71) while maintaining the same relative positions of the helices on the two cylinders, thereby causing the knives to engage one another at new points, so that should grooves or dents develop in the knives they could be so adjusted as to bring said grooves or dents at different relative points on the two knives.

The web is fed from the printing cylinders to the slitting cylinders by means of the feed rolls 28 which are geared together and one of which is driven by a belt 80 from a pulley on the shaft of the upper impres-

sion cylinder 24. After leaving the slitting cylinders the strips 43 may be received upon a belt or other conveyer 81 of any suitable form.

It will of course be understood that the relative arrangement of the printing surfaces 45 and 45^x on the printing cylinders and the knives 69 and 69^x on the slitting cylinders is such that the web 26 is slit along lines between the strips or columns of printing. In order to secure accuracy in the position of the cuts made in the web the position of the slitting cylinders in the frame may be adjusted by means of the adjusting screws 61, as above explained.

Having thus described my invention, I claim:

In a printing machine, a printing cylinder and a printing plate comprising a plurality of sections secured to said cylinder and having interengaging serrated edges, said sections having printing surfaces which collectively constitute a continuous printing surface wound about said cylinder in the form of a helix, said edges being perpendicular to said helix across the convolutions of said printing surface and substantially parallel to said helix between said convolutions.

In testimony whereof I affix my signature, in presence of two witnesses,

JOHN FLINN ANCONA.

Witnesses:

G. B. TUTHILL,
C. D. ANCONA.
